(57) **CLAIM**

The ornamental design for a lamp with a base as shown and described.

DESCRIPTION

FIG. 1 is a top perspective view of the first embodiment of a lamp with a base;

FIG. 2 is a bottom perspective view thereof;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof;

FIG. 9 is a bottom perspective view with the dial in a first exemplary position;

FIG. 10 is a bottom perspective view with the dial in a second exemplary position;

FIG. 11 is an exploded, bottom perspective;

FIG. 12 is a top perspective view of a second embodiment of a lamp with a base; and,

FIG. 13 is a bottom perspective view thereof.

Broken lines are for illustrative purpose only and form no part of the claimed design.
